DESIGN FOR A COMBINED LAMP AND SUPPORT

Wilbur Henry Adams and Dean H. Holden,
Cleveland, Ohio

Application January 2, 1937, Serial No. 66,876

Term of patent 3½ years

To all whom it may concern:

Be it known that we, Wilbur Henry Adams and Dean H. Holden, both citizens of the United States and both residing in Cleveland, in the county of Cuyahoga and State of Ohio, have invented a new, original, and ornamental Design for a Combined Lamp and Support, of which the following is a specification, reference being had to the accompanying drawing, forming a part thereof, in which:

Fig. 1 is a perspective view of the lamp support member shown in Fig. 4;

Fig. 2 is a plan view thereof;

Fig. 3 is a side elevational view thereof, and
Fig. 4 is a side elevational view of the combined lamp and support showing our new design.

The dominant feature of our design resides in the support member.

We claim:

The ornamental design for a combined lamp and support substantially as shown and described.

In testimony whereof, we hereunto affix our signatures this first day of December, 1936.

WILBUR HENRY ADAMS.
DEAN H. HOLDEN.
